STOCK COMPANY OF SWITZERLAND

TRANSFORMER STRUCTURE

Application filed October 2, 1931, Serial No. 566,434, and in Germany September 17, 1931.

This invention relates to improvements in transformer structures and particularly to transformers to be used for the purpose of supplying alternating current to the parallel operating anodes of an electric power rectifier of the metal inclosed metallic vapor type.

Six phase electric power rectifiers of the metal inclosed metallic vapor type generally have a number of anodes which is a multiple of six so that a plurality of anodes per phase are connected in parallel. The arc drop characteristic in rectifiers is, however, drooping, especially when the current increases from zero, and the arc drop characteristic is rising only from a certain current load. An additional voltage drop must therefore be produced in the several anode circuits in order that the several parallel connected anodes of the same phase may be forced to carry a uniform current. Such additional drop can be obtained by means of anode reactance coils or by dividing the secondary winding of each phase of the rectifier supply transformer in as many separated windings as there are parallel operating anodes. Such division of the supply transformer winding is not, however, in general, sufficient to produce the necessary drop especially in the use of low direct voltages in rectifiers where the absolute amount of the stray voltage is small. A combination of both of the above named arrangements, namely, the separation of the transformer secondary windings of the parallel operating anodes of a rectifier into a plurality of sections with the addition of reactances has already been proposed. Such arrangement, however, has the disadvantage that the additional reactances make it very expensive.

It is, therefore, an object of the present invention to provide a device for increasing the stray voltage drop in the secondary windings of a transformer supplying parallel operating anodes of an electric power rectifier.

Another object of the invention is to provide a device for increasing the stray voltage drop in the secondary windings of a transformer supplying parallel operating anodes of an electric power rectifier in which trans-

former the secondary winding portions are uniformly distributed relative to the primary winding and are interleaved with each other.

Another object of the invention is to provide a device for increasing the stray voltage drop in the secondary windings of a transformer supplying parallel operating anodes of an electric power rectifier in which transformer the secondary winding portions are interleaved relative to each other and in which means are arranged in the stray path of the several winding portions to increase the stray voltage of such portions.

Another object of the invention is to provide a device for increasing the stray voltage drop in the secondary windings of a transformer supplying parallel operating anodes of an electric power rectifier in which transformer the secondary winding portions are uniformly distributed over the primary winding and are interleaved with each other and in which means in the form of cut out rings or cylinders of a good conductive material are arranged in the stray path of the several winding portions to increase the stray voltage of such portions.

Objects and advantages, other than those above set forth, will be apparent from the following description when read in connection with the accompanying drawing in which:

Figure 1 illustrates a portion of a transformer structure, partially in section, embodying the present invention; and

Figs. 2 and 3 illustrate modifications of the means for increasing the stray flux of the transformer.

Referring more particularly to the drawing by characters of reference, reference numeral 4 designates a fragment of a transformer core on which is wound a primary winding 5 which is surrounded by a secondary winding divided into sections 6, 7, 8 and 9. The secondary winding sections are similar and are uniformly distributed over the entire length of the primary winding. The several secondary winding sections are connected into series connected groups for the purpose of supplying parallel operating anodes of an electric power rectifier and the

several sections of the several groups are interleaved. Thus secondary winding sections 6 and 8 are connected to form one group and sections 7 and 9 form another group. It is 5 desirable that the connections of the several groups be such that current flows through the groups in opposite directions to minimize the mechanical stresses on the structure. It will be understood that the windings of only one 10 phase of a transformer structure have been shown and that the secondary windings have been shown as divided into only two groups to supply two parallel operating anodes of a rectifier. The secondary winding may, however, be divided into any number of groups 15 dependent only on the number of anodes to be supplied in parallel and provided only that the sections of the winding groups be interleaved and uniformly distributed over the 20 primary winding.

An insert of good magnetic conductive material such as iron is arranged between each 25 two of the sections of the secondary winding and in spaced relation therefrom and from the primary winding. Such inserts are in the form, preferably, of interrupted rings to avoid short circuits thereof. The rings may be solid as shown at 10 or may be made laminated with the several laminations spaced 30 from each other as shown at 11. Under some circumstances it may be desirable to imbed each of the laminations within insulation as shown at 12 and to unite the several insulated laminations by pressure.

The stray voltage drop in the secondary 35 windings is very much increased even at very low currents by the use of inserts such as above described. As soon, however, as the inserts are saturated the stray voltage drop 40 will no longer increase proportionately with a further increase in current which is an advantage for the reason that the stray voltage drop will not become too great at full load or at overload on the transformer. The stray 45 flux in the secondary winding sections can also be increased by the use of magnetic material inserts at points other than those shown, but the arrangement of interrupted rings of magnetic material between the winding sections is the simplest and the safest 50 arrangement in operation.

Although but one embodiment of the present invention has been illustrated and described, it will be apparent to those skilled 55 in the art that various changes and modifications may be made therein without departing from the spirit of the invention or from the scope of the appended claims.

60 The invention claimed is:

1. In an electric transformer, a core, a primary winding upon said core, a secondary winding divided into a plurality of sections arranged in spaced relation over said 65 primary winding, and means arranged ad-

jacent said secondary winding to increase the voltage drop thereof.

2. In an electric transformer, a core, a primary winding wound upon said core, a secondary winding divided into a plurality of sections connected into groups, the groups being uniformly distributed over said primary winding, and means arranged adjacent said secondary winding to increase the voltage drop thereof. 75

3. In an electric transformer, a core, a primary winding wound upon said core, a secondary winding divided into a plurality of sections connected into groups, the groups being arranged in interleaved spaced relation over said primary winding, and inserts of magnetic material arranged between each pair of said secondary winding sections. 80

4. In an electric transformer, a core, a primary winding wound upon said core, a secondary winding divided into a plurality of sections connected into groups, the groups being arranged in interleaved spaced relation and being uniformly distributed over said primary winding, and inserts of conductive material arranged between each pair of said secondary winding sections and in spaced relation therefrom to increase the voltage drop thereof. 85

5. In an electric transformer, a core, a primary winding wound upon said core, a secondary winding divided into a plurality of sections connected into groups, the groups being arranged in interleaved spaced relation and being uniformly distributed over said primary winding, and inserts of conductive material arranged between each pair of said secondary winding sections and in spaced relation therefrom to increase the voltage drop thereof, said inserts being laminated. 90

6. In an electric transformer, a core, a primary winding wound upon said core, a secondary winding divided into a plurality of sections connected into groups, the groups being arranged in interleaved spaced relation and being uniformly distributed over said primary winding, and inserts arranged between each pair of said secondary winding sections and in spaced relation therefrom to increase the voltage drop thereof, said inserts comprising laminations of conductive material and sheets of insulation arranged between the laminations. 100

7. In an electric transformer, a core, a primary winding wound upon said core, a secondary winding divided into a plurality of sections connected into groups, the groups being arranged in interleaved spaced relation and being uniformly distributed over said primary winding, and inserts arranged between each pair of said secondary winding sections and in spaced relation therefrom to increase the voltage drop thereof, said inserts being in the form of interrupted rings formed 110

from laminations of conductive material and sheets of insulation arranged between the laminations.

8. In an electric transformer comprising a winding divided into a plurality of sections divided into a plurality of groups, the sections of the respective groups being arranged in interlaced spaced relation, and means disposed in said spaces between the said sections to increase the voltage drop of said sections.

10 9. In an electric transformer comprising a winding divided into a plurality of sections arranged in spaced relation, and means arranged adjacent the respective sections of said winding for increasing the voltage drop thereof.

15 In testimony whereof we have hereunto subscribed our names this 18th day of September A. D. 1931.

CERTIFICATE OF CORRECTION.

Patent No. 1,890,045.

December 6, 1932.

STEFAN WIDMER, ET AL.

It is hereby certified that error appears in the printed specification of the above numbered patent requiring correction as follows: Page 1, in the heading to printed specification, date of filing application in Germany, for "September 17, 1931" read "September 17, 1930"; and that the said Letters Patent should be read with this correction therein that the same may conform to the record of the case in the Patent Office.

Signed and sealed this 23rd day of May, A. D. 1933.

M. J. Moore.
